US0D1039035S

(12) **United States Design Patent** (10) **Patent No.:** **US D1,039,035 S**
(45) **Date of Patent:** **** Aug. 13, 2024**

(54) **GLASSES**

(71) Applicant: **LUXOTTICA S.r.l.**, Agordo (IT)
(72) Inventor: **Claudio Renon**, Voltago Agordino (IT)
(73) Assignee: **LUXOTTICA S.R.L.**, Agordo (IT)
(**) Term: **15 Years**
(21) Appl. No.: **29/866,632**
(22) Filed: **Sep. 21, 2022**
